UNITED STATES PATENT OFFICE.

EARL C. HANSON, OF WASHINGTON, DISTRICT OF COLUMBIA.

LIFEBOAT RADIOSIGNALING SYSTEM.

1,320,390

Specification of Letters Patent.

Patented Nov. 4, 1919.

Application filed February 20, 1919. Serial No. 278,179.

To all whom it may concern:

Be it known that I, EARL C. HANSON, a citizen of the United States, residing at Washington, in the District of Columbia, 5 have invented certain new and useful Improvements in Lifeboat Radiosignaling Systems, of which the following is a specification.

My invention relates broadly to radio 10 communication systems, and more particularly to a system for signaling to and from lifeboats.

The object of this invention is to provide 15 a radio telephone or telegraph system adapted for installation on lifeboats for use in emergency signaling.

A further object of this invention is to utilize a suitable floating antenna to be retained on a suitable insulated reel and connected to radio signaling apparatus to be described hereinafter.

A still further object of the invention 25 is to provide a helmet to be worn by the operator, which contains a telephone receiver and telephone transmitter, the purpose of the helmet being to eliminate extraneous sounds when operating the signaling system.

Other and further objects of the invention 30 will in part be obvious and will in part be pointed out in the following specification and set forth in the appended claim.

Figure 1 of the drawings represents diagrammatically the radio transmitting and 35 receiving signaling apparatus installed on a life boat in combination with a floating antenna and operator's helmet, together with means for manually controlling the signaling apparatus, as a telegraph transmitter.

Fig. 2 is a cross-sectional view of the floating antenna.

Referring to Fig. 1, reference character 1 shows a section of a lifeboat equipped with 40 radio telephone and telegraph apparatus indicated at 2. 3 shows an antenna reel mounted on an insulated support 5. 4 indicates a floating antenna adapted to be wound on the drum of the reel 3. This 45 floating antenna will be more fully described hereinafter as set forth in Fig. 2. The antenna 4 is connected to the radio signaling apparatus through insulated conductor 6.

Ground plate 11 is connected through lead 11^a to the aforementioned signaling apparatus. 7 is a waterproof helmet similar to the type of head gear used in aircraft radio systems. The helmet contains a telephone receiver 8 connected with the signaling apparatus by conductors within waterproof casing 8^a. 9 is a telephone transmitter secured in helmet 7 and connected with the radio telephone transmitting apparatus in case 2 by conductors in waterproof casing 9^a.

The radio signaling apparatus contained in case 2 can be controlled as a radio telephone transmitter by employing transmitter 9. The signaling apparatus can also be controlled for telegraphic purposes by means of a key 10 connected to case 2 through waterproof leads 10^a. The signaling apparatus in case 2 is substantially protected by waterproofing material against salt spray.

Referring to Fig. 2, the floating antenna comprises a flexible metallic conductor 4 surrounded by a suitable insulating sheathing 4^a, around which is placed buoyant material 4^b, as cork, for example. This buoyant material is retained by an outer protecting waterproof casing 4^c.

The material employed in the construction of the floating antenna is of such a character that the cable will be sufficiently flexible to be readily wound on the retaining reel.

With the combination of apparatus described, reliable telephonic and telegraphic radio communication can be maintained to and from lifeboats and used in cases of emergency. It is possible, by changing the 90 effective length of the floating antenna by winding out or recoiling, to control the wave length of the radio signaling system.

What I claim is:

In a radio signaling system for lifeboats, 95 the combination of radio signaling apparatus, means for controlling said radio signaling apparatus by speech or signal means, and a buoyant antenna connected to one side of said radio apparatus, adapted to be 100 coiled on a reel when in inoperative position, said reel being insulated from the lifeboat, and an earth plate connected to the said radio signaling apparatus.

EARL C. HANSON.
